COMBINED SUPPORT ARM FOR EXTENSIBLE LAMP AND SERVICE OUTLET CONTROL PANEL

Mitchell Bobrick, Pacific Palisades, Calif., assignor to
P. N. Luminous Equipment Co., Franklin Park, Ill.

Filed June 23, 1967, Ser. No. 7,572

Term of patent 14 years

Int. Cl. D26—02

U.S. Cl. D48—20

FIG. 1.

FIG. 2.

FIG. 3.

FIG. 4.

FIG. 1 is a side elevational view of a support arm for lamps and the like with the arm in a retracted position;
FIG. 2 is a front elevational view;
FIG. 3 is an enlarged, top plan view;
FIG. 4 is an enlarged, bottom plan view; and
FIG. 5 is a side elevational view, with the arm extended.
The broken line showing of a lamp head is for illustrative purposes only.

I claim:

The ornamental design for a combined support arm for extensible lamp and service outlet control panel, as shown and described.
